UNITED STATES PATENT OFFICE.

ISAAC J. WITHAM, OF HUDSON FALLS, NEW YORK, ASSIGNOR OF ONE-HALF TO GEORGE S. WITHAM, SR., OF HUDSON FALLS, NEW YORK.

PULP-FEED REGULATOR.

1,233,738.

Specification of Letters Patent. Patented July 17, 1917.

Application filed April 14, 1917. Serial No. 161,985.

To all whom it may concern:

Be it known that I, ISAAC J. WITHAM, a citizen of the United States, residing at Hudson Falls, in the county of Washington 5 and State of New York, have invented certain new and useful Improvements in Pulp-Feed Regulators, of which the following is a specification.

In the manufacture of paper, paper pulp, 10 of which the paper is made, is fed in a continuous stream to an endless belt which supports the pulp until it has become sufficiently firm to support itself on the drying rollers over which it is finally carried in the 15 form of a continuous web to suitable reeling mechanism. It has been found, however, that it is impossible to maintain the pulp at a constant consistency or density, and if care is not taken to regulate the continuous 20 flow of pulp onto the supporting belt according to its density, paper of varying thickness will result. Although it is the usual custom to regulate the flow of the pulp by manually operated valves, some attempts have been made to automatically 25 control the flow of the pulp by floats disposed in tanks from which the pulp is fed, or to compensate for any variation in the density of the pulp by correspondingly in- 30 creasing or decreasing the speed at which the supporting belt is moved by means of feelers constantly in contact with the paper web which detect any variation in thickness therein, and which are electrically connected 35 to the belt driving motor, to vary the speed of the motor according to the variations. Inasmuch as the floats in the feed tank were operated not only by the density of the pulp, but also by the necessary surge and variation 40 of liquid level in the tank, and inasmuch as an actual variation had to result in the paper web already formed before the feeler could operate, it was impossible to construct an apparatus sensitive to the slightest variations of density and which would give accuracy and evenness to the finished paper. 45

The object of this invention is to provide means for automatically regulating the flow

of the pulp, such means being responsive to the variation in the electric conductivity 50 of the pulp due to its varying density.

A further object of the invention is to render the regulating means adjustable to insure the desired thickness of the paper.

A further object of the invention is to 55 provide a simple device for determining the density of the pulp in order to properly regulate its flow.

In carrying out the invention two pairs of electrodes, one in each line of a shunted electric circuit, are suspended in the pulp feed tank. Each pair of electrodes is connected in series with a resistance, one of the resistances being preferably variable. Bridged across the shunted circuits, connecting the 60 electrodes and the resistance in each circuit, is the field coil of a motor. I may also connect a galvanometer adapted to register in terms of density in parallel with the motor field. The motor whose field is 65 bridged across the electrode circuits may operate a fly ball governor to open or close a valve controlling the pulp feed opening, according to the speed at which the motor is run. When pulp is introduced into the 70 feed tank an electric circuit flows across the gap between the electrodes, the amount of current varying inversely with the resistance of the pulp. This variation produces a corresponding variation in the speed of 75 the motor to operate the feed valve.

It will be understood that I do not limit my invention to use in connection with paper pulp, as it is equally applicable for determining the density of other pulps, and regulating the flow thereof. Neither do I limit myself to the express construction herein set forth.

Referring to the drawings,

Figure 1 is a somewhat diagrammatic view 90 showing my invention applied to a pulp feeder.

Fig. 2 is a diagrammatic representation of the circuits employed in carrying out my invention.

Fig. 3 is a detailed view showing a par-

ticular form of governor mechanism for operating the valve.

Fig. 4 shows my particular arrangement of circuits connected to a recording galvanometer adapted to register in terms of density.

Fig. 5 merely shows an enlarged view of the recording device.

In the drawings, A represents a stuff or pulp feed box, having an inlet a , a stuff feed opening a^1 , a launder a^2 , in front of the opening, and an overflow a^3 whereby it is possible to maintain the pulp in the tank at a constant depth irrespective of the amount being introduced into the tank or being fed therefrom, in order to maintain the pressure at the feed opening a^1 constant. To control the flow of the pulp through the feed opening a^1 there is provided a valve B shown as a sliding gate mounted on a rock shaft b , pivoted in a suitable bearing C fixed to the floor of the tank. The opposite end of the rock shaft b is connected by means of a link b^1 to a second rock shaft D pivoted in a bearing E on the tank A. The other end of the rock shaft D is pivotally connected to an upright rod F passing through the bearing block G, the gear H, and the hollow shaft H' carried by the gear H (Fig. 3). The upper end of the rod F is enlarged and has therein a circumferential groove into which is loosely fitted an annular collar i pivotally connected to the lifting arms i^1 of a fly-ball governor I by links i^2 . The lifting arms i^3 of the governor are pivoted on a rod i^3 carried by the hollow shaft H' and operate up and down in slots h formed in the hollow shaft. The gear H is mounted in the bearing block G.

The gear H is driven through suitable reducing gearing J by a shunt wound direct current motor K. In addition to the ordinary field coil K^1 connected in series with the usual resistance K^2 (see Fig. 2) shunted across the brushes k , k , there is provided an auxiliary field coil L connected independently of the field K^1 and adapted to increase or decrease the speed of the motor. The motor is connected with any suitable source of direct current through lines O and P at k^3 and k^4 .

Suspended in the pulp feed tank are two pairs of electrodes M and N. One of the electrodes M is connected at m to wire P leading from a source of direct current. The other electrode M is connected in series with a resistance r in a suitable resistance box R with the other wire O leading from a source of direct current at o . One of the electrodes N is connected to the wire O at n . The other electrode N is connected in series with a resistance r^1 in the resistance box R to the wire P at p . In series also with the electrodes N, but shunted across the resist-

ance r^1 is a variable resistance or rheostat R' 65 by the variation of the resistance of which the current flowing through the circuit n p may be regulated. Connected to the circuit mo at point s between M and r and to the circuit n p at point t between N and r and 70 R' is a bridge circuit leading through the auxiliary field L of the motor K. This arrangement forms the well known Wheatstone bridge circuit, having for its four arms the circuits mp s , mp t , on s , and on t , and 75 having for its shunt circuit the auxiliary field coil circuit s t (see Fig. 2). I may also connect a recording galvanometer U adapted to register in terms of density in parallel with the auxiliary field circuit at 80 points u and u' .

In operation, pulp of normal consistency is first introduced into the tank A. The resistance of the rheostat R' is then adjusted so that no current flows across the bridge circuit. The motor K is then started. It is run at a speed suitable to cause the fly-ball governor I to open the valve or gate B sufficiently to feed the proper amount of pulp of normal thickness. If there is any variation 90 in the density of the pulp, its electric conductivity is varied accordingly, and more or less current may flow across the electrodes M and N. This variation of current across the electrodes destroys the electrical balance 95 of the bridge and causes a current to flow across the bridge. If the current flows in one direction, the magnetic field of the coil L tends to strengthen the field of the usual field coil K', thereby increasing the speed of 100 the motor and causing the fly-balls to lift higher to open the valve. If the current passes through the field coil in the opposite direction the magnetic field produced by 105 the auxiliary coil tends to neutralize the effect of the field K' to retard the speed of the motor. Should it be desired to vary the thickness of the finished paper, the variable resistance R' is moved to vary the speed of 110 the motor and permit more or less pulp to pass through the feed opening a^1 .

In Figs. 4 and 5 I have shown the use of the electrodes and a galvanometer to determine the density of the pulp, apart from the use of a motor to regulate the feed.

I claim as my invention:

1. In a pulp feed receptacle, electrodes within the receptacle, and a recording galvanometer in the electrode circuit to determine the density of the pulp.

2. In a pulp feed regulator, a pulp receptacle having a feed opening, a valve for controlling said opening, and means for actuating said valve comprising a motor having a source of current and an auxiliary field winding, and electrodes within the receptacle and in circuit with the auxiliary field, whereby the variations in density of the

pulp will increase or decrease the field strength of the motor to open or close said valve.

3. In a pulp feed regulator, a pulp receptacle having a feed opening, a valve for controlling said opening, an electric motor, electrodes within the receptacle and in circuit with a field winding of the motor, and

a governor mechanism for controlling said valve and itself regulated by the speed of the motor as the density and conductivity of the pulp varies.

In testimony whereof, I have hereunto subscribed my name.

ISAAC J. WITHAM.
